United States Patent Office

Des. 227,161
Patented June 5, 1973

227,161

EYEGLASS FRAME FRONT

Howell S. Jobbins, Jr., Warwick, R.I., assignor to Universal Optical Company, Inc., Providence, R.I.

Filed Dec. 6, 1971, Ser. No. 205,437

Term of patent 14 years

Int. Cl. D16—06

U.S. Cl. D57—1 F

FIG. 1.

FIG. 2.

FIG. 3.

FIG. 1 is a front elevational view of an eyeglass frame front showing my new design.

FIG. 2 is a top plan view thereof.

FIG. 3 is a side elevational view thereof.

I claim:

The ornamental design for an eyeglass frame front, substantially as shown.
